UNITED STATES PATENT OFFICE

JOSEPH H. SHEARD, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA

HINGE

Application filed September 14, 1928. Serial No. 305,897.

This invention relates to hinge construction and, more particularly, to that type generally designated "friction" hinges; that is to say, hinges capable through established resistivity to hold a structure supported thereby at any desired open position without the assistance of independent securing means.

The primary object of this invention is the provision of an improved type of friction hinge, the engaging components whereof are of a nature to withstand atmospheric action and will not bind or rust under continued exposure.

Another object is to provide a hinge of the above noted character including adjusting means whereby the requisite coefficient of friction, to ensure continuous serviceability, may be maintained.

A further object is the provision of a friction hinge devoid of projecting parts of an obstructive or interfering character, the same being capable of adjustment without the use of special tools or other equipment.

A still further object is to provide hinges of the type referred to that are simple in design, cheap to manufacture, and which are devoid of complicated or expensive parts.

With the foregoing and other objects in view, the nature of my invention will be best understood by reference to the accompanying sheets of drawings, illustrative of convenient embodiment thereof, which will now be described in detail; it being premised, however, that various constructive changes and other arrangements of the several parts may be resorted to, without departing from the spirit or scope of said invention, as defined in the appended claims.

In the drawings:—

Fig. I is a respective view of one form or "close-up" type of friction hinge embodying the present improvements.

Fig. II is an exploded perspective view of the several hinge components in disassembled relation.

Fig. III is a broken horizontal section through a typical casement window equipped with the hinge of Fig. I.

Fig. IV is a similar elevational view looking toward the left hand of the preceding figure.

Fig. V is a front elevation looking to the right hand of Fig. IV.

Fig. VI is a perspective view of a modified or double "close-up" friction hinge embodying the present improvements.

Fig. VII is a vertical sectional view showing the application of the modified form of this invention to a transom ventilator arranged to swing upwardly from the bottom.

Fig. VIII is a top plan view of the same; and,

Fig. IX is a front elevation thereof. Like characters of reference are applied to corresponding parts in all the views.

Referring more particularly to Figs. I to V, inclusive, the structure chosen for convenience of illustration comprises a metallic jamb or window frame 1, whereof the perimeter rails are formed from bar stock of Z-shaped cross-section; while the sash frame or casement 2 is fabricated from corresponding material, and closes against the window frame 1, with its face flange 3 overlapping the complementary flange 4 of the latter frame; said parts constituting no feature of the present invention and being merely referred to by way of clarifying its adaptation in use.

My novel friction hinge, comprehensively designated 5 in Figs. I and II, comprises a "male" component or stationary member 6 with a "female" component or movable member 7. The former of these components or the stationary member 6 embodies an irregularly configured body portion 8 with a planarly offset anchorage pad 9 having apertures 10 therethrough whereby it is secured to the window frame 1 by the medium of appropriate attaching means, such as screws 11. The stationary member body portion 8, remote from the offset pad 9, is reduced in thickness and retroverted to provide a grippage overlap 12 which, with said body portion, affords a U-shaped clevis, for a purpose later on explained. Holes 13, 14 are, respectively, formed in the body portion 8 and grippage overlap 12, while the for-

mer—or both—of said holes is screw-threaded for engagement by a stud bolt or adjuster pindle 15.

The other hinge component or movable member 7, embodies co-planar anchorage pads 16, 16' conveniently—although not essentially—disposed in rectangular relation, having apertures 17 whereby said member is attached to the sash casement 2, through the medium of cap screws 18, for example. Integrally formed with the movable member 7, and appropriately at right angles thereto, is a lateral outset or apertured ear 19 constituting the journal portion of said movable member. This lateral outset or apertured ear 19, it will be seen, is reinforced relative to the anchorage pads 16, 16' by its integral heel and brace portions 20, 21, respectively.

20 In connection with my novel friction hinge 5, I make use of friction-creating means such as washers 22. These washers 22 constitute an important feature of my invention which is to make the friction surfaces of materials 25 that will not bind or rust together under exposure, and yet will offer a sufficiently high co-efficient of friction. To this end I fabricate the hinge components before described of such material as steel, malleable 30 iron forgings, or the like; whereas, the washers 22 are preferably made of bronze, brass, copper, lead, hard fiber or other suitable material, as I find such combinations of unlike 35 metals or materials effectively restrain relative movement of the respective parts one over the other, without undergoing appreciable wear incident to continuous usage. Accordingly, in assembling the hinge components, I preferably employ two of the 40 washers 22, one disposed above and the other below the journal portion or apertured ear 19 of the movable hinge member 7, when said ear is inserted in the U-shaped or clevis end of the stationary member 6, pivotal connection between these members being obtained by application of the adjuster pindle 15, in an obvious manner.

Referring now to Figs. VI to IX, inclusive, it is to be particularly noted that while the hinge assemblage illustrated therein differs somewhat from the disclosure hereinbefore set forth that the fundamentals correspond, with the exception that the specific type of hinge shown is adapted for the support of adjoining movable casements. Accordingly, those parts which have their equivalents in the preceding description are similarly designated, with differing reference characters only applied where necessary. Firstly it is to be observed that the modified form of hinge, herein comprehensively marked 23, comprises a stationary member 24, and a pair of movable members 7, 7'; the latter strictly conforming with

the preceding explanation other than being right and left counterparts.

The stationary member 24, however, is substantially in the form of a short-leg T; that is to say, it embodies co-planar anchorage pads 25, 25' with apertures 26 whereby it is securable through the medium of screws 11 to the window frame 1. Integral with the stationary member 24 is a short leg or apertured bracket projection 27 that affords support for the pindle adjuster screws 15 on which the movable members 7, 7' are pivoted, with interposed washers 22, as before explained. Particular attention is directed to the fact that the function of the hereinbefore described grippage overlap or clevis 12 is, in this form of my invention, relegated to an apertured stirrup-member 28 which engages the outer washers 22, as best shown in Figs. VI and VIII.

From the foregoing it is thought that my invention will be well understood, but I wish to herein stress the fact that any requisite adjustment is easily effected by each pindle screw 15, and that when sufficient tension is placed thereon, it exerts a pressure on the washers 22 and, in turn, on the bearing portions of the associated stationary member 6 or 24. This degree of tension, obviously, determines the amount of pressure, and consequently the degree of friction or resistance which the stationary parts 6 or 24 offer to the engaging surfaces of the co-operative moving member 7, 7'.

Furthermore, it will be understood that hinges of the typified character embodying a clevis 12 or stirrups 28 and combination of "unlike" metals or materials require no oiling or lubrication; that they do not involve "sill" hardware on the window frames which interfere with a clear unobstructed view through the sash or casement panes; and, finally that they are designed to ensure an even distribution of friction irrespective of the angular degree of sash—or the like—opening relative to the frame therefor.

Having thus described my invention, I claim:

1. In a friction hinge of the type described, a stationary member embodying a bearing clevis, a movable member with an outset apertured projection, an adjuster pindle sustained by the stationary member with passage through the clevis and apertured projection, and friction members of a different material to the aforesaid parts intervening the co-operative portions of the hinge stationary and movable members.

2. In a friction hinge of the type described, a stationary member embodying a grippage bearing clevis, a movable member having a lateral apertured journal projection integral therewith, an adjuster pindle taking through the clevis and apertured journal projection, and friction washers of

a different material to that of the aforesaid parts intervening the clevis components and journal projection with capacity for compression under varied tensioning of the adjuster pintle.

5 3. In a friction hinge of the type described, a stationary member comprising a body portion with an integral attaching pad and a flexible apertured bearing clevis, a movable member having a journal projection integral therewith, an adjuster pintle taking through the clevis and journal projection, and friction washers of a different material to that of the aforesaid parts intervening the clevis components and journal projection with capacity for compression under varied tensioning of the adjuster pintle.

10 4. In a friction hinge of the type described, a stationary member comprising an irregularly-configured element having a planarly-offset anchorage pad and a relatively-remote retroversion constituting a flexible bearing clevis, a movable member having a journal projection integral at right angles thereto, an adjuster pintle taking through the clevis and journal projection, and friction washers of a different material to that of the aforesaid parts intervening the clevis components and journal projection

15 with capacity for compression under varied tensioning of the adjuster pintle for the purpose specified.

20 5. In a friction hinge of the type described, a stationary member of irregular configuration with a planarly-offset anchorage pad and a relatively remote retroversion constituting a flexible bearing clevis, a movable component embodying integral anchorage pads and a lateral apertured ear for reception in the clevis bearing, an adjuster pintle taking through the clevis and apertured ear, and friction washers of a different material to that of the aforesaid parts intervening the clevis members and apertured ear with capacity for compression under varied tensioning of the adjuster pintle.

25 6. In a friction hinge of the type described, a stationary member of irregular configuration with a planarly-offset anchorage pad and a relatively remote retroversion constituting a flexible clevis bearing, a movable member embodying co-planar anchorage pads disposed at right angles with a lateral apertured ear at the angular portion thereof, an adjuster pintle taking through the clevis bearing and apertured ear, and friction washers of a different material to that of the aforesaid parts intervening the clevis components and apertured ear with capacity for compression under varied tensioning of the adjuster pintle.

30 7. In a friction hinge of the type described, a stationary member of irregular configuration with a planarly-offset anchorage pad and a relatively remote retroversion

of substantially U-shape constituting a flexible clevis bearing, a movable member embodying co-planar anchorage pads disposed at right angles with a lateral journal ear at the angular portion thereof, said ear being 70 re-enforced by integral heel and brace sections, an adjuster pintle screw-threaded into the clevis bearing and passing through the journal ear, and friction washers of a different material to that of the aforesaid parts 75 intervening the clevis bearing components and journal ear with capacity for compression under varied tensioning of the adjuster pintle.

8. In a friction hinge of the type described, as stationary member of irregular configuration with an integral planarly-offset anchorage pad and a substantially U-shaped clevis bearing, a movable member embodying rectangular-disposed anchorage 85 pads with an integral reenforced journal projection adapted to intervene the clevis bearing, an adjuster pintle threadedly engaging one or both of the clevis bearing components with free passage through the journal projection, and friction washers intervening said clevis components and journal projection with capacity for varied compression for the purpose specified.

9. In a friction hinge of the type described, a stationary member of T-formation; counterpart movable members, each embodying a rectangular anchorage pad with an integral reenforced journal projection, co-operative with the leg of the T-member, an adjuster pintle passing through each journal projection and threadedly engaging the T-member leg, friction washers intervening the co-operative portions aforesaid, and an apertured stirrup for clamping said parts in 105 frictional engagement under varied tensioning imposed on the respective adjuster pintles.

10. In a friction hinge of the type described, a stationary member of short-leg T-formation the cross portion whereof constitutes aligned anchorage pads, counterpart movable members each embodying a rectangular anchorage pad with an integral reinforced journal projection co-operative 110 with the leg of the T-member, all of said anchorage pads being allocated to a common plane, an adjuster pintle passing through each journal projection and threadedly engaging the T-member leg, friction washers 115 intervening the cooperative portions aforesaid, and an apertured stirrup for clamping said parts in frictional engagement under varied tensioning imposed on the respective adjuster pintles.

11. In a friction hinge of the type described, a stationary member embodying an irregularly-configurated body portion with an integral planarly-offset anchorage pad and a substantially U-shaped flexible bearing 120

65

clevis; a movable member, embodying rectangularly-disposed anchorage pads with an integral reenforced journal projection adapted to the clevis bearing; an adjuster pintle engaging one or both of the bearing clevis components with free passage through the journal projection; and friction washers intervening said clevis components and journal projection with capacity for varied compression by the adjuster pintle, for the purpose specified.

12. In a friction hinge of the type described, a stationary member of short leg T-formation with the cross portion adapted as aligned anchorage pads; counterpart movable members, each of which comprises a rectangular anchorage pad with an integral re-enforced outset journal projection at the angular corner thereof; all of the aforesaid anchorage pads being allocated to a common plane; an adjuster pintle passing through each journal projection and threadedly engaging the T-member leg; friction washers intervening the respective co-operative portions; and an apertured stirrup for clamping said parts in frictional engagement under varied tensioning imposed on the individual adjuster pintles.

13. In a friction hinge of the type described, the combination of a stationary component comprising an irregularly-configured body portion with an integral planarly-offset anchorage pad, said body portion remote from the offset pad being reduced in thickness and retroverted to form a substantially U-shaped flexible bearing clevis.

In testimony whereof, I have hereunto signed my name at Philadelphia, Pennsylvania, this 5th day of September, 1928.

JOSEPH H. SHEARD.
